CLAIM

The ornamental design for an exterior surface configuration of climate control unit for motor vehicle, as shown and described.

DESCRIPTION

FIG. 1 is a front view of an exterior surface configuration of climate control unit for motor vehicle according to our novel design; and,

FIG. 2 is a perspective view from the front right of an exterior surface configuration of climate control unit for motor vehicle according to our novel design, the louvers is a raised position from that shown in FIG. 1.

The dash line showing included depicts environment and is not part of the claimed design.

The surface(s) or portion(s) of the article not shown in the drawing or described in the specification forms(s) no part of the claimed design.
